US0D1051762S

(12) **United States Design Patent** (10) Patent No.: **US D1,051,762 S**
(45) Date of Patent: ** Nov. 19, 2024

(54) **PENDANT**

(71) Applicant: **RICHEMONT INTERNATIONAL SA**, Villars-sur-Glâne (CH)

(72) Inventor: **Clément Boireau**, Annecy (FR)

(73) Assignee: **RICHEMONT INTERNATIONAL SA**, Villars-sur-Glâne (CH)

(**) Term: **15 Years**

(21) Appl. No.: **35/516,232**

(22) Filed: **Jan. 6, 2023**

(80) **Hague Agreement Data**

Int. Filing Date: **Jan. 6, 2023**

Int. Reg. No.: **DM/226334**

Int. Reg. Date: **Jan. 6, 2023**

Int. Reg. Pub. Date: **Feb. 10, 2023**

(51) LOC (14) Cl. **11-01**

(52) U.S. Cl.

USPC **D11/79**

(58) **Field of Classification Search**

USPC D11/1-5, 79

CPC A44C 5/20; A44C 5/2042

See application file for complete search history.
